(57) **CLAIM**

The ornamental design for a display screen or portion thereof with graphical user interface, as shown and described.

DESCRIPTION

FIG. 1 is a front view of a display screen or portion thereof with graphical user interface showing our new design; and, FIG. 2 is another front view of the display screen or portion thereof with graphical user interface as shown in FIG. 1. The broken lines showing the display screen or portion thereof and portions of the graphical user interface form no part of the claimed design.
